UNITED STATES PATENT OFFICE.

JOHN C. WILLIAMS, OF ANITA, IOWA.

HARROW.

SPECIFICATION forming part of Letters Patent No. 309,119, dated December 9, 1884.

Application filed May 31, 1884. (No model.)

To all whom it may concern:

Be it known that I, JOHN C. WILLIAMS, a citizen of the United States, residing at Anita, in the county of Cass and State of Iowa, have 5 invented certain new and useful Improvements in Harrows; and I do declare the following to be a full, clear, and exact description of the invention, such as will enable others skilled in the art to which it appertains to make and 10 use the same, reference being had to the accompanying drawings, and to the letters and figures of reference marked thereon, which form a part of this specification.

My invention relates to harrows; and it consists in the novel parts presently described, constructed, combined, and arranged substantially as will be hereinafter more fully described and claimed.

In the drawings, Figure 1 is a plan view of 20 my harrow. Fig. 2 is a side view of one end thereof. Figs. 3, 4, and 5 are detail views representing the tooth and holder. Figs. 6 and 7 are detail views of the joint presently described.

25 The end beams, A, of the harrow are composed of the top bar, A', and the bottom bar, A², held together by the clamping devices presently described. The beams may be provided at their opposite ends with hooks A³ by bending the ends of the upper bar, as most clearly 30 shown in Fig. 1. My design in this is to enable the coupling by suitable links of several harrow-sections, so as to form a wide harrow, as will be understood. The blocks B are placed 35 between the bars A' A², and formed with a vertical mortise, B', fitted to receive the harrow-bars, and made of a depth less than the vertical height of said harrow-bars. These mortises are preferably made from the underside 40 of the block; but may, when so desired, be formed from its upper side without involving a departure from the broad principles of my improvement. I also provide these blocks with side grooves, B², fitted to receive the 45 clamping-bolts C C, whereby the blocks are held in place and the harrow-bars clamped to the front and rear end beams. Instead of having the bottom bar, A², extended entirely 50 across the ends of the harrow, it may be cut off on opposite sides of the mortised blocks, sufficient length being provided for the passage of the clamping-bolts. The harrow-bars D are

set vertically edgewise and within the mortise B', and when the bolts C are tightened the bars D are clamped firmly to the end beams. By 55 loosening the bolts the bars may be adjusted longitudinally through the mortised blocks, as desired. It will be seen that I employ one of these joint-blocks at each end of each of the harrow-bars. The bars D are set vertically 60 edgewise, and secured to the end beams in the manner before described. I bend the bars D to form the end wings, D' D', and the intermediate wing, D², both said wings being set at an angle to the end beams and to each other. 65 By this arrangement I secure such a disposition of the teeth that the width of the harrow will be thoroughly worked in the operation of the device. The braces E are secured at one end to the harrow-bars at the angle of wings 70 D' D², and extend thence to the end beams, and are secured thereto and preferably extended in advance of said beams, and bent to form the hooks E', to which the draft may be coupled. I call these hooks the "draft-hooks," and they 75 are provided at both ends of the harrow, so it may be drawn in either direction, as desired. It will be noticed that these braces are secured on the bars D on the side opposite that to which the end wings are inclined, and I consequently only employ one on each of the extreme side bars. The number of bars D may be increased at will; but ordinarily I find three 80 a desirable number, and when a wider harrow is wished for several sections should be connected, as before indicated. By setting the harrow-bars vertically edgewise it will be noticed they are greatly strengthened against bending in a vertical plane, and a lateral 85 springing is provided for, which renders the 90 harrow easy-going and the draft lighter, as will be appreciated. This lateral springing is greatly enhanced by bending the harrow-bars as shown and described, and it is for this and other purposes before described I prefer to so 95 bend them. The teeth are secured on and adjustable along these bars preferably in the manner presently described. The tooth-holder F is made open on one side, and has formed in its edge walls from said open side slots, F', 100 fitted to the side of the holder. A clamping-bar, F², extends across this open side of the holder, and on the opposite side of the harrow-bar, and the bolts F³ F³ are passed transversely

through the said clamping-bar and the holder, and when these bolts are tightened the holder and tooth G are secured firmly to the harrow-bar. By loosening the bolts the holder and tooth may be adjusted along the harrow-bar to any desired point, as will be understood from Figs. 1 and 2. The tooth G is bent at its upper end to form the right-angled arm G'. In operation this arm G' extends over and rests on the top of the harrow-bar, and bears on its under side against said bar, and on its upper side against the rounded crown F' of the holder, forming a pivot on which the tooth may be turned so as to bring it against the vertical side F⁵ or the inclined side F⁶ of the holder, according as it is desired to have a straight or inclined toothed harrow. The harrow, it will be understood, is drawn from one end when desired to have a straight tooth, and from the other end when it is desired to have the teeth inclined.

My harrow is simple in construction, effective in operation, and can be made at slight cost.

25 Heretofore harrow-teeth have been formed with right-angled arms at their upper ends, serving as journals on which the teeth may be turned to adjust them into a straight or inclined position against straight or inclined walls suitably formed in the holders, and this I do not broadly claim as my invention; but,

Having thus described my invention, what I claim, and desire to secure by Letters Patent, is—

35 1. The combination of the harrow-bars, the end beam having upper and lower bars, the joint-blocks mortised vertically to receive the harrow-bars, and provided in their opposite sides with grooves, and the clamping-bolts fitting into said grooves and connecting the bars of the beam, substantially as set forth.

2. The combination, with the double-barred end beams and the harrow-bars, of the joint-blocks provided with vertical mortises fitted 45 to the harrow-bars, and with vertical bolt-grooves on its opposite sides, substantially as set forth.

3. In a harrow, the combination of the harrow-bars, the holder having straight and in-

clined walls, and provided in one side with a 50 mortise, F', fitted to the bar, and having its crown extended laterally over said mortise, and the tooth held in said holder and having its upper end bent laterally, and extended and bearing between the top of the bar and the 55 crown of the holder, substantially as set forth.

4. The combination of the bar, the holder secured alongside the bar and formed with a straight and an inclined wall, and having its crown projected above the bar, and adapted 60 on the under side of said crown to serve as a bearing for the arm of the tooth, and the tooth held in the holder, and having its upper end bent, forming a right-angled arm extended and bearing between the upper side of the bar and 65 the under side of the crown, substantially as set forth.

5. In a harrow, the herein-described holder, provided with a straight and an inclined wall, and having in one side a mortise, F', fitted to 70 receive the harrow-bar, and having its upper side or crown, F', adapted on its under side to serve as a bearing for the tooth-arm, and extended laterally over the mortise F', substantially as set forth.

6. The harrow, substantially as herein described, consisting of the bars D, set vertically edgewise, bent to form the intermediate and end wings, D² D', the tooth-holders F, provided with a mortise, F', fitted to the bars D, 80 and secured thereagainst, and having crown F', extended laterally over the bars, the tooth G, secured in the holder, and having arm G' extended and bearing between the crown F' and the top of the bars, the end bearing, A, 85 consisting of bars A' A², the block B, placed between said bars A' A², and provided with mortise B', fitted to receive the bars D, and edge grooves B², and the clamping-bolts C C', all arranged and combined substantially as 90 set forth.

In testimony whereof I affix my signature in presence of two witnesses.

JOHN C. WILLIAMS.
